[57] CLAIM

The ornamental design for a boat, as shown and described.

DESCRIPTION

FIG. 1 is a perspective view of a boat showing a first form of our new design;

FIG. 2 is a top plan view thereof;

FIG. 3 is a front elevational view thereof;

FIG. 4 is a rear elevational view thereof;

FIG. 5 is a perspective view of a second form of our boat design;

FIG. 6 is a top plan view of the boat of FIG. 5;

FIG. 7 is a front elevational view of the boat of FIG. 5;

FIG. 8 is a rear elevational view of the boat of FIG. 5;

FIG. 9 is a side elevational view of the left side of the boats of FIGS. 1 and 5, the right sides being mirror images of the left sides; and,

FIG. 10 is a bottom plan view of the boats of FIGS. 1 and 5.
